UNITED STATES PATENT OFFICE.

JOHN L. STEVENS, OF CHICAGO, ILLINOIS, ASSIGNOR TO EDWARD HEMPSTEAD, OF SAME PLACE.

EGG-CARRIER.

SPECIFICATION forming part of Letters Patent No. 279,199, dated June 12, 1883.

Application filed April 6, 1883. (No model.)

To all whom it may concern:

Be it known that I, JOHN L. STEVENS, a citizen of the United States, residing in Chicago, in the county of Cook and State of Illinois, have invented a new and useful Improvement in Egg-Carriers, of which the following is a specification.

In the present invention the tray is composed of a single piece of straw-board, the four exterior walls of the tray being formed by scoring the straw-board a suitable distance from its edges and turning up the scored portions to form the walls of the tray. The ends of the scored portions are provided with tenons and mortises for locking the same firmly together, and the walls are braced and strengthened by intermediate transverse partitions or supports which divide the tray into four equal parts, each part being designed to contain, preferably, about nine eggs.

In the drawings, which form a part of this specification, and in which similar letters of reference indicate like parts, Figure 1 is a perspective view of a device embodying my invention. Fig. 2 is a plan view, showing the straw-board before its edges are folded up; and Fig. 3 is a plan view of the intermediate cross braces or supports folded.

In the drawings, A represents the straw-board of which the tray is composed, preferably of a square form.

B B are the exterior walls of the tray. The walls B are formed by scoring the board A, as indicated in dotted lines at Fig. 2, at a. The walls B are provided with mortises b and tenons b', the tenons having a notch, b², in their upper edges, whereby the adjacent walls B B are notched and held firmly together. Each wall B may be provided with a tenon at one end and a mortise at the other; or the tenons may be on both ends of one wall and the mortises on both ends of the other.

C represents the intermediate vertical cross braces or supports. Each of these cross-braces is provided with notches c, extending half across their width at each end, and a similar notch, c', at its middle, and the walls B are each provided with a half-notch, c², at their

middle, whereby the intermediate cross-braces C are interlocked with the exterior cross-walls 50 B of the tray. The tenons b' are cut beveling on their under edges, as shown at d, and may preferably be cut beveling at their upper edges also, as shown at d', so that the tenons and mortises of the adjacent walls may be easily 55 locked together.

The exterior walls, B, of the tray being integral with the board A and united thereto along their entire length, and the adjacent walls being securely interlocked together by 60 the tenons and mortises, affords a very strong and rigid construction, especially when the walls are braced by the intermediate cross-pieces, C C.

If preferred, the cross-braces C C may be 65 provided with tenons and mortised into the walls B B, instead of interlocked by the simple notches shown.

The tenons b', being provided with a notch, b², at their upper edges only, permits of the 70 adjacent walls being readily interlocked together when integral with the board A.

When the carrier is being shipped empty the walls B are laid out flat, as shown in Fig. 2, and the cross-pieces C C folded, so that the 75 whole will occupy very small compass.

By this construction I am enabled to make a very cheap, strong, and durable tray, in which eggs may be safely packed and transported, and any number of trays can be tiered 80 one on top of another, owing to the great strength and rigidity of the vertical walls B and the cross-supports C.

I claim—

The combination of board A, exterior walls, 85 B, integral therewith, provided with mortises b and tenons b', having notches b² in their upper edges, and the intermediate cross-supports, C, interlocked with each other and with the walls B, substantially as specified.

Dated Chicago, March 29, 1883.

JOHN L. STEVENS.
